UNITED STATES PATENT OFFICE.

WILLIAM P. THOMPSON AND ROBERT P. THOMPSON, OF PHILADELPHIA,
PENNSYLVANIA.

FLUID-PRESSURE-REGULATING VALVE.

SPECIFICATION forming part of Letters Patent No. 613,737, dated November 8, 1898.

Application filed February 2, 1898. Serial No. 668,805. (No model.)

To all whom it may concern:

Be it known that we, WILLIAM P. THOMPSON and ROBERT P. THOMPSON, citizens of the United States, residing at Philadelphia, 5 county of Philadelphia, and State of Pennsylvania, have invented a new and useful Improvement in Valves for Reducing and Regulating Pressure of Fluids, of which the following is a full, clear, and exact description, 10 reference being had to the accompanying drawings, which form a part of this specification.

Our invention has for its object certain improvements upon the valves and method for 15 reducing and regulating pressure of fluids.

We will first describe the invention as illustrated in the accompanying drawings and then specifically point out the invention.

In the drawings, Figure 1 is a vertical sectional view illustrating the preferred form of embodiment of our invention. Fig. 2 is a vertical sectional view showing a modified form of embodiment of our invention. Fig. 3 is a front view of pitman H.

25 A is the inlet from the source of pressure-supply to the valve-chamber, and B the outlet from the valve-chamber. In this valve-chamber is a differential valve consisting of the members C and D, connected by the valve-stem E. The valve member C controls the port c and the valve member D the port d. As may be seen from the construction, the incoming pressure-supply acts upon these 30 two valve members oppositely to force the valve C upon its seat and to lift the valve D off its seat. As these two valve members are connected together by the valve-stem E, the effective surface is the difference in area between the valve member D, the larger, and

35 the valve member C, the smaller. This differential area may be quite small. As may be seen, the valve-stem is longer than the distance between the faces of the valve-seats, and also the lifting or larger valve member 40 D is made cup or dome shaped. The stem is made of a metal whose coefficient of expansion is less than that of the metal of which the valve members are formed. In practice we prefer to make the stem of steel and the 45 valve members of brass. The purpose of this is that under the action of heat the stem ex-

pands, and in the ordinary construction when the valve members are lifted from their seats and returned again toward the seat the valve C would seat, while the valve D would not 55 unless this was corrected. With our improved construction, however, while the valve-stem E will expand, the length of the stem being greater than the distance between valve-seats enables the dome shape of one of 60 the valves to be of a size sufficient to cause the depending parts to expand sufficient to compensate for the expansion of the stem. The shell carrying the valve-seats is always under the action of the atmosphere, while 65 the stem is directly subjected to the action of the heat. If the stem between the valve shoulders or points of attachment to the valves was only equal, or substantially so, to the distance between the valve-seats under the ac- 70 tion of heat, it would be impossible to properly seat both valves. By the use of a stem larger than the distance between valve-seats we can form the dome-shaped member D, which will expand in a reverse direction to that 75 of the stem, and its expansion will compensate for the difference of the expansion of the stem and shell, and as a consequence, the expansion being thus equalized, there will be no difficulty in always seating both valve 80 members.

Projecting from the valve member D is a clip e.

F is a crank-arm guided in the clip e. This crank F is fixed on a rock-shaft F'. At the 85 opposite end of the rock-shaft is a lever G, having upon it the movable weight G'.

H is a pitman connecting the lever G with the lever H', pivoted at h and having upon it beyond the pivot the weight h'.

I is an arm projecting from the lever H' between the pitman H and the pivot-point h of the lever H'. This projecting arm I rests against a diaphragm-valve J, held in a casing K in the ordinary manner. This diaphragm-valve is in communication with a water-chamber L through the medium of a passage l, having the throttle portion l'. The water-chamber L is in connection with the passage B through the inlet B'.

100 The general purpose of apparatus of this kind is to automatically control the delivery

of fluid from a high-pressure supply into a low-pressure service—that is, to reduce the pressure—and to control the reduced pressure under variations in the high-pressure supply 5 and preventing the draft from reduced pressure lowering the high-pressure supply to less than a fixed minimum.

In general the operation is as follows: The weight G' is set for the lowest pressure which 10 it is desired to maintain in the boiler—that is, the pressure below which it is not desired under any conditions to allow fluid to pass through the valve from the boiler to the discharge B —while the weight h' is set at the 15 highest desired pressure to be reached in the low or reduced pressure system. Initially, when the pressure in the boiler or in the pipe A arises above that to which the weight G is set the valve, by pressure upon the member 20 D , is lifted, and the fluid flows through the passages d and c into the passage B . From the passage B it also flows through the passage B' into the water-chamber L and from thence through the passage l and throttle- 25 passage l' to the diaphragm-valve J . When the pressure in the pipe B has risen to the limit set by the weight h' , the diaphragm-valve J is operated, which, through the medium of the lever H' , pitman H , and connections, again seats the valve members D and 30 C and cuts off the supply. When the pressure in the pipe B falls below that set by the weight h' , the diaphragm-valve J is returned and the valve members D and C allowed to 35 again rise from their seat.

The great advantage in this construction is caused by the form of the member D of the differential valve D C and by making the valve members D and C of more heat-expansible material than the connecting - stem E 40 and making the length of the connecting-stem greater than the distance between valve-seats,

thus making the seating of both members D and C of the differential valve certain.

Having now fully described our invention, 45 what we claim, and desire to protect by Letters Patent, is—

1. A differential valve consisting of a plurality of members connected by a stem, the portion of the stem between points of attachment of valve members being of length greater than the distance between the seats of the valve members, the valve members being of greater heat-expansible metal than the stem. 50

2. A differential valve consisting of a plurality of members connected by a stem, the portion of the stem between points of attachment of the valve members being of length greater than the distance between the seats of the valve members, the lifting-valve member being of greater heat-expansible metal 55 than the stem. 60

3. A differential valve consisting of a plurality of members connected by a stem, the portion of the stem between the points of attachment of the valve members being of length greater than the distance between the seats of the valve members, the lifting-valve member being made cup or dome shaped. 65

4. A differential valve consisting of a plurality of members connected by a stem, the portion of the stem between points of attachment of the valve members being of length greater than the distance between the seats of the valve members, the lifting-valve member being cup or dome shaped, and of greater heat-expansible metal than the stem. 70 75

Signed by us, at Philadelphia, this 26th day of January, 1898.

WILLIAM P. THOMPSON.
